Primary Examiner—Melody N Brown(74) *Attorney, Agent, or Firm*—Fross Zelnick Lehrman & Sissu, P.C.; Lawrence E. Apolzon, Esq.(57) **CLAIM**

The ornamental design for a radiator grill for automobile, as shown and described.

DESCRIPTION

FIG. 1 is a perspective view of the top, front, and right side of a radiator grill for automobile showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The elements shown in broken lines are for illustrative purposes only and form no part of the claimed design.
